UNITED STATES PATENT OFFICE

105,259

DESIGN FOR A PRINTING PRESS UNIT FRAME

James L. Blackley, Battle Creek, Mich., assignor
to The Duplex Printing Press Company, Battle
Creek, Mich., a corporation of Michigan

Application November 6, 1936, Serial No. 65,734

Term of patent 7 years

To all whom it may concern:

Be it known that I, James L. Blackley, a citizen
of the United States, residing at Battle Creek,
in the county of Calhoun and State of Michigan,
have invented a new, original, and ornamental
Design for a Printing Press Unit Frame as shown
in the accompanying drawing, forming part of
this specification.

In the drawing:

Fig. 1 is an elevational view of the plating end

of the printing press unit frame showing my new
design;

Fig. 2 is an elevational view of the opposite
side or drive end thereof.

Fig. 3 is a top plan view of the frame.

I claim:

The ornamental design for a printing press
unit frame, substantially as shown.

JAMES L. BLACKLEY.
